UNITED STATES PATENT OFFICE.

ANTHONY DAUL, OF BROOKLYN, ASSIGNOR TO GUSTAV HEERBRANDT, OF NEW YORK, N. Y.

CHURN.

SPECIFICATION forming part of Letters Patent No. 380,553, dated April 3, 1888.

Application filed December 2, 1887. Serial No. 256,738. (No model.)

To all whom it may concern:

Be it known that I, ANTHONY DAUL, of Brooklyn, in the county of Kings and State of New York, have invented certain new and useful Improvements in Churns, of which the following is a specification.

This invention relates to an improved churn which is specially adapted for family use, inasmuch as butter may be readily made by the same, even from small quantities of cream, within a comparatively short time, so that families can supply their own want and obtain thereby a better quality of butter.

The invention consists of a churn the essential element of which is a horizontally-reciprocating semicircular cradle, in which is supported a glass vessel or jar by means of an adjustable cross-head and transverse straps or bands connected to the cradle. The cradle is guided by eyes on fixed parallel rods of the supporting-frame and made of two adjustable sections, so as to be adapted to different sizes of vessels. The cradle-sections are provided with slots for attaching the retaining-straps to the same.

In the accompanying drawings, Figure 1 represents a side elevation, partly in section, of my improved churn. Fig. 2 is a plan of the same; Fig. 3, a vertical transverse section on line $x-x$, Fig. 1; and Fig. 4, a detail vertical longitudinal section of the cradle.

Similar letters of reference indicate corresponding parts.

Referring to the drawings, A represents the supporting-frame of my improved churn, which frame consists of two upright standards, $a a$, which are attached to a suitable base-board, A' , and connected by longitudinal rods a' , which are rigidly attached to the standards a , and which serve to form the guideways for the horizontally-reciprocating cradle B. The cradle B is provided with eyes or sleeves b , by which it is guided on the rods a' . The cradle is made semicircular in shape, preferably of sheet metal, and provided with solid heads. A vessel or jar, C, of glass or other suitable material, is firmly secured in horizontal position in the cradle B by cork or other elastic layers, $d d$, which are interposed between the bottom and stopper of the jar C, and by an ad-

justable cross-head, C', that serves to hold the stopper in the neck of the vessel. The cross-head C' is adjusted to the size of the jar C by a threaded shank, e , passing through the head of the cradle, and by a thumb-screw nut, e' , and jam-nut e'' , as shown in Figs. 1 and 2. Transverse bands or straps C^2 , of sheet metal or other suitable material, serve to attach the vessel to the body of the cradle B by springing the ends of the straps into slots f of the cradle, as shown clearly in Fig. 3. A number of parallel slots are arranged in the cradle, so as to admit the use of a larger or smaller jar or vessel. The cream is placed in the vessel, upon which the same is closed, placed in position in the cradle, and secured to the same by the cross-head and straps. When this is done, the cradle is ready for the churning operation. Reciprocating motion is then imparted to the cradle by suitable driving mechanism, which consists of a driving gear-wheel, g , having a crank-handle, g' , and a transmitting-pinion, g'' , keyed to a crank-shaft, g^3 . A pitman, g^4 , connects the crank of the crank-shaft g^3 with the cradle, as shown clearly in Fig. 2. In place of the driving gear-wheels, a belt-and-pulley transmission, or any other device by which reciprocating motion may be imparted to the cradle, may be employed.

The cradle may be made of two adjustable sections, which are arranged to telescope one over the other, both being provided with slots that register with each other, so as to permit the adjustment of the transverse fastening-straps. Between the vessel or jar C and the cradle B is preferably interposed a layer of felt, that serves as a cushioning for protecting the vessel against injury.

The churn is worked by taking hold of the driving-handle and turning the same, so as to impart reciprocating motion to the cradle by the transmitting mechanism described. This shakes up the cream in the vessel and churns it by a repeated succession of shakings in the direction of the motion imparted thereto, so that the butter-globules are effectually separated from the remaining parts of the cream, and thereby butter of superior quality and taste produced in from five to ten minutes. The vessel is then removed from the cradle and the

butter and buttermilk taken out of the same. The vessel is then cleaned and ready for use again. In this manner a handy and convenient churn for domestic purposes is obtained 5 that enables even small families to make their own supply of butter for table use.

Having thus described my invention, I claim as new and desire to secure by Letters Patent—

- 10 1. The combination of a supporting-frame having longitudinal guide-rods, a cradle having sleeves or eyes guided on said rods and slots, an adjustable cross-head, a jar or vessel in said cradle, transverse straps for attaching the jar to the cradle, and mechanism for im-
15 parting longitudinally-reciprocating motion to the cradle, substantially as set forth.

2. In a churn, the combination of a cradle formed of two semicircular sections provided with slots, a cross-head adjustable in the head of the cradle, a vessel or jar, and transverse 20 straps extending over the vessel and connected to the slots of the cradle, substantially as set forth.

In testimony that I claim the foregoing as my invention I have signed my name in presence 25 of two subscribing witnesses.

ANTHONY DAUL.
